TEMPERING UNIT

John T. Midyette, Jr., Cumberland
Court House, Va.

Application April 8, 1949, Serial No. 86,297

2 Claims. (Cl. 236—12)

1

This invention relates to tempering units of the general type employed in hot water supply systems to effect the mixing of cold water with hot water in such proportions as to insure against delivery of water at an excessive temperature to any service outlet with which the supply system may be equipped.

Although the tempering unit embodying the present invention may be employed in various types of hot water supply systems, it is herein illustrated in connection with a system of the type wherein a heating coil is employed in association with a typical oil burning home heating furnace.

The primary object of the present invention is to provide a simple, inexpensive and efficient tempering unit which is structurally so characterized as to enable it to be produced in its entirety from standard parts which are readily obtainable on the open market and may be easily assembled with reference to each other in producing a complete unit, thus obviating the necessity of special tools for use in its manufacture and at the same time insuring its user against the difficulty of obtaining replacement parts if and when such parts might be required.

Other objects and advantages of the invention will become apparent from the following description when taken in connection with the accompanying drawings, in which:

Fig. 1 is a schematic view, showing generally an oil-burning furnace with which is associated a hot water supply system having incorporated therein a tempering unit embodying the present invention.

Fig. 2 is a central vertical sectional view of the tempering unit and illustrating its functioning position in relation to the heating coil of Figure 1, and

Fig. 3 is a view showing the tempering unit in elevation.

Referring generally to Figure 1, the numeral 10 indicates a conventional home heating furnace, adapted to be fired, as by any standard oil burner unit 11, and from which its heating medium, such as hot water, may be conducted to various radiators, not shown, by way of a suitable piping system fragmentally indicated by the numeral 12.

With the furnace 10, there is associated a hot water supply system 14 by which hot water for all house-hold purposes may be delivered to such faucets or other similarly controlled outlets, not shown, as are required at various locations in the home, such as at the kitchen sink, in the bathroom and elsewhere.

2

The system 14 includes a heating coil or unit 15 so arranged within the usual water compartment of the furnace 10 that it is surrounded or enveloped at all times by the water content of the furnace. The lower and upper legs 16 and 17 of the heating coil pass outwardly through the side wall of the furnace and are connected, respectively, by way of T-couplings T—T' to cold water supply and hot water delivery pipes 18 and 20, the former of which is adapted to communicate with a suitable water source and the latter of which may be connected to various faucets or other hot water outlets wherever desired. It will be understood, of course, that the cold water supply pipe 18 may be conveniently utilized, in conjunction with its associated branch line 21, to supply water as required to the water compartment of the furnace. Also, it will be understood that the cold water supply pipe 18

20 may be equipped with a branch line 22 by way of which cold water may be delivered to such faucets or other similarly controlled outlets, not shown, as are required either independently of or in close association with the hot water outlets 25 to which the hot water delivery pipe 20 may lead.

In order to insure against delivery of water at an excessive temperature to any service outlet with which the hot water supply system 14 may be equipped, there is provided a thermally controlled tempering unit 24, which is disposed intermediate the cold water supply pipe 18 and the hot water delivery pipe 20 where it is adapted to so function when any one of the hot water outlets is opened as to permit passage of such quantity of cold water from the pipe 18 into the pipe 20 at its point of connection with the upper leg 17 of the heating coil 15 as to thereby reduce any excessive water temperature to a predetermined range value of, say, 135° F. to 145° F., thus obviating all possibility of the existence of any unduly high temperature in the hot water as it is drawn from the system by way of any one or more of its service outlets.

As will be best understood from an inspection of Figures 2 and 3, the tempering unit 24 consists of various standard parts which readily lend themselves for use in the assembly constituting the present invention. In this connection, it will be noted that the body-like housing of the unit 24 comprises a pipe coupling which includes a male section 25 and a female section 26, the central passage of the former of which is so formed as to provide a spring receptacle 27, a valve-stem passage 28, a valve chamber 30 and a valve seat 31. The lower screw threaded end of the section 25 is

adapted to receive the internally screw threaded section 26, within which is seated a pipe section or nipple 32, between the upper end of which and the lower end of the section 25 is clamped the peripheral margin of a disk-like valve guide 34. With the guide 34, there is associated a vertically displaceable check-valve 35, the stem 36 of which passes through the central opening of said guide and is equipped at its lower end with a cup-like disk 37, on which is carried a compression spring 38 which engages said guide from beneath and serves to normally maintain said valve in its seated position.

The upper end of the male section 25 is screw threaded throughout a portion of its length so as to receive the internally screw threaded end of a pipe nipple 40 and is of a reduced outside diameter throughout the remainder of its length so as to provide an annular flange 41 forming with said nipple an annular channel C, the purpose of which will hereinafter more clearly appear. Within the upper end of the annular flange 41 there is sweated, or otherwise suitably secured, the lower end of an inverted cup-like housing 42, within which is located a Sylphon bellows 44, the lower end of which is suitably sealed, as by a closure 45, provided on its outer face with a disk-like contact-button 46. The bellows 44 is soldered, or otherwise suitably connected, at its upper end to the end wall of the housing 42 and is maintained in communication with a bulbous capillary tube 47, the lower end of which passes through the end wall of said housing and is there soldered or otherwise suitably connected to it. The bellows 44 and its associated capillary tube 47 contains a suitable expansible medium, adapted, in accordance with well known practice, to so respond to temperature changes as to cause the bellows to expand and contract longitudinally of itself.

Within the chamber 30 there is located a control valve 51, the stem 52 of which projects upwardly through the passage 28 and into the receptacle 27 where it is provided at its upper end with a button-like head 54, adapted to receive the downward thrust of the bellows 44 and the upward thrust of a compression spring 55 which is disposed about said stem and is seated on the bottom wall of said receptacle.

It is important, as will hereinafter appear, that communication be maintained at all times between the channel C and the spring receptacle 27, and to this end there are provided in the annular flange 41 a pair or more of orifices 56, each leading directly from said chamber to said channel, the latter of which opens directly into a similar channel C' surrounding the cylindrical wall of the housing 42.

As will be understood from Figure 2, when taken in connection with Figure 1, the tempering unit 24 may be conveniently incorporated in the system 14 by connecting the nipple 32 to the coupling T by way of a short length of pipe 57 and by connecting the nipple 40 to the coupling T', the latter connection being such that the bulbous capillary tube 47 lies within the path of flow of water from the leg 17 of the heating coil 15 to the hot water delivery pipe 20.

The branch line 21 leading from the cold water supply line 18 to the water compartment of the furnace 19 is equipped with a standard hand operated control valve 58 by which communication between the supply line and water compartment may be conveniently established or severed at will. In accordance with usual prac-

tice, the cold water supply line 18 may be, and preferably is, equipped with a standard type of check valve indicated generally by the numeral 60 and herein illustrated as located intermediate the coupling T and the point at which said supply line joins its associated branch line 21.

Before entering upon a detail discussion of the operation of the present embodiment of the invention, it may be well to generally mention 10 that the valve 51 and its associated actuating means, namely, the capillary tube 47, bellows 44, and spring 55 are so related that the valve is 15 fully open during such time as said tube is subjected to a temperature of, say, 145° F. or more and is adapted to move toward and into its closed position as such temperature drops from that value to, say 135° F.

Taking into account the foregoing description 20 of the invention, it will be understood that as water is drawn from the heating coil 15 by way of the hot water delivery pipe 20 such water will 25 pass upwardly about the capillary tube 47. If the water thus drawn from the heating coil 15 is at a temperature greater than 145° F. it will so affect the content of the capillary tube 47 and the bellows 44 as to cause the latter to expand longitudinally of itself. Such expansion of the bellows 44 will cause the valve stem 52 to so move 30 downwardly against the action of its associated compression spring 55 as to open the valve 51, thus permitting cold water to pass upwardly from the supply line 18 through the tempering unit 24 by way of the check valve 35, passage 28, spring receptacle 27, orifices 56, channels C-C', and thence on into the coupling T' where it comes into the hot water as it passes from the leg 17 into said coupling. Mixing of the cold water with the hot water in the manner just described lowers the temperature of the hot 35 water as it is supplied to the hot water delivery pipe 20 to a non-scalding value of 145° F. As the hot water is further tempered or lowered in temperature, the bellows 44 correspondingly contracts lengthwise of itself and thus permits 40 the valve 51 to move towards its closed position under the action of the spring 55. The valve 51 assumes its fully closed position at such time as the water in the vicinity of the capillary tube 47 reaches a temperature of 135° F. and is maintained in such position so long as the temperature of that water does not exceed 135° F. However, when the temperature of the water in the vicinity of the capillary tube 47 again rises above 45 135° F., the valve 51 is opened under the expanding action of the bellows 44 and to an extent ranging from barely open to fully open depending upon the extent to which the temperature of the water in the vicinity of the capillary tube is raised, it being remembered that fully open 50 position of the valve is attained when such temperature reaches a value of 145° F. and is maintained in that position until the ambient temperature of the capillary tube is lowered to effect a closing movement of the valve as and for the 55 purpose previously described.

When the hot water supply system 14 is in a static or balanced condition, as when all outlets of the delivery pipe 20 are closed, the check-valve 35 is maintained closed by its associated 60 spring 38, thus obviating the possibility of any thermo-syphon effect with respect to the water content of the circuit which includes the tempering unit 24, and the heating coil 15 together with its associated legs 16 and 17. However, when 65 the valve 51 is open and water is being drawn

from the hot water delivery pipe 20 by way of any one of its service outlets, the check valve 35 is free to move to its open position to permit the passage of water from the cold water supply pipe 18 through the tempering unit 24 and on into the coupling T' where it, upon reaching the vicinity of the capillary tube 47, comes into contact with water being delivered to that vicinity from the heating coil 15.

Although only one form of the invention is herein shown and described it will be understood that various changes may be resorted to without departing from the spirit of the invention, as for example, the coupling T' may be of the screw threaded type instead of the sweated type herein illustrated, and in that event the upper end of the male section 25 could be screw threaded directly connected to the lower arm of such substitute coupling, thus eliminating from the assembly the pipe nipple 40 which in the present instance serves to connect said male section to the T-coupling herein illustrated.

What is claimed is:

1. For use in a hot water supply system of the type including a heating unit having lower and upper legs connected respectively to cold water supply and hot water delivery pipes, a tempering unit adapted to be connected to said pipes in shunt relation to said heating unit and comprising a body-like housing in the form of a pipe coupling consisting of a male section and a female section connected to each other, the male section having a central passage and being provided with a tubular extension forming a spring receptacle and having a diametrically reduced end portion provided with an orifice leading outwardly from said receptacle, a pipe nipple connected to said tubular extension and forming with said end portion an annular channel communicating with said orifice, a T-coupling having three arms—one connected to said pipe nipple and its others being adapted for connection, respectively, with said upper leg and said hot water delivery pipe, a control valve including a stem located, in part, within said central passage and, in part, within said spring receptacle, a spring located within said receptacle and acting on said stem to move said valve from its open position to its closed position, a Sylphon bellows disposed in alignment with said stem and containing an expansible medium, a cup-like housing connected to said reduced end portion of said tubular extension and forming with said pipe nipple an annular upper channel communicating with said spring receptacle by way of said lower annular channel and said orifice, a capillary tube communicating with said bellows and containing an expansible medium, said capillary tube being located in the path of communication afforded between said hot water delivery pipe and said heating unit by way of said T-coupling, whereby its contained expansible medium in association with that of said

bellows will cause said bellows to expand lengthwise of itself to effect opening movement of said valve against the opposing action of said spring as the ambient temperature in the vicinity of said capillary tube rises above a predetermined value, said opposing action of said spring being utilized to effect closing movement of said valve incident to a drop in said ambient temperature to a value below said predetermined value.

2. For use in a hot water supply system of the type including a heating unit having lower and upper legs connected respectively to cold water supply and hot water delivery pipes, a tempering unit adapted to be connected to said pipes in shunt relation to said heating unit and comprising a body-like housing including a pipe coupling consisting of a male section and a female section connected to each other, the male section having a central passage and a spring receptacle communicating with each other and being provided with an orifice leading outwardly from said receptacle, a T-coupling connected to said male section for communication with said spring receptacle by way of said orifice and adapted for connection with said upper leg and with said hot water delivery pipe, a central valve including a stem located, in part, within said central passage and, in part, within said spring receptacle, a spring located within said receptacle and acting on said stem to move said valve from its open position to its closed position, a Sylphon bellows disposed in alignment with and acting on said stem to move said valve from its closed position to its open position, a cup-like housing connected to said male section in a surrounding relation to said bellows, a capillary tube connected to said cup-like housing and containing an expansible medium, said capillary tube being located in the path of communication afforded between said hot water delivery pipe and said heating unit by way of said T-coupling, whereby its contained expansible medium will cause said bellows to so move as to effect opening movement of said valve against the opposing action of said spring as the ambient temperature in the vicinity of said capillary tube rises above a predetermined value, said opposing action of said spring being utilized to effect closing movement of said valve incident to a drop in said ambient temperature to a value below said predetermined value.
